FURNACE AND STOKER

Virgil C. Kline, Floral Park, N. Y.

Application April 28, 1936, Serial No. 76,735

14 Claims. (Cl. 110—46)

This invention relates to a new furnace and stoker for consuming solid comminuted fuel, the invention being particularly applicable to domestic household heating furnaces.

It is the primary object of the invention to provide, in a device of this character, an under-feed stoker which will supply the required amount of fuel and maintain it properly distributed around the furnace with sufficient agitation to prevent excessive clinker formation.

It is a further object to maintain the fuel bed adjacent the outer walls of the furnace for securing increased efficiency from the apparatus.

Referring to the drawings wherein I have shown the preferred embodiments of my invention,

Fig. 1 is an elevational view of one form of apparatus constructed in accordance with the present invention.

Fig. 2 is a horizontal view thereof, partly in section, taken on the line 2—2 of Fig. 1.

Fig. 3 is a vertical sectional view taken on the line 3—3 of Fig. 2.

Fig. 4 is an enlarged fragmentary view of the base plate of the fire pot showing the distributor ring in position.

Fig. 5 is a sectional view thereof taken on the line 5—5 of Fig. 4.

Fig. 6 is a bottom plan view of the distributor ring shown in Figs. 4 and 5.

Fig. 7 is a view similar to Fig. 2 showing a modification of my invention.

Fig. 8 is a vertical sectional view of the line 8—8 of Fig. 7.

Fig. 9 is an enlarged cross-sectional view of the fuel-feeding device taken on the line 9—9 of Fig. 7.

Fig. 10 is a longitudinal section taken on the line 10—10 of Fig. 9, and

Fig. 11 is an enlarged fragmentary transverse sectional view of the devices for moving the distributing ring, shown in Fig. 7.

In the first form of the invention, the furnace 1 is a typical domestic boiler furnace, having a water-jacketed section 2 and a supporting base 3. The furnace has a usual fuel door 4, a clinker doorway at 5, and an ash pit doorway at 6. In place of the usual grates, I provide a fuel-supporting frame comprising a base plate 8 and an upstanding portion 9, forming in the embodiment shown a frustum of a cone at the center of the furnace. The base plate 8 preferably extends outwardly under the side wall 2 of the furnace. The upstanding portion 9 may form a continuation of the base plate or be separately

formed and secured upon the base plate, as will be understood. The portions 8 and 9 together with the side wall 2 form a fire pot 10, the portion 9 being formed with a number of air passages 9a for admitting air to the fuel in the fire pot.

The upstanding wall 9 may be protected by removable perforated plates 11, constructed of metal, tile or the like, bolted or otherwise held in position thereon. The upper edge of the portion 9 is covered by one or more rings 12, formed with air passages 13 leading outwardly from the space within the wall 9 to the fire pot. A cap plate 14, which may be of sufficient weight to maintain the rings in position, or else bolted to said rings, is mounted above rings 12.

The cap plate 14 and rings 12 form a central opening through which ash discharges into passage 15 formed by pipe 16 leading to the passage 18 of the ash conveyor 20. This conveyor is shown as a typical screw conveyor for removing ash from the space beneath the passage 15 and discharging the same outside of the furnace into a container (not shown).

The base plate 8 may be formed with a series of slots or openings 22 to admit additional combustion-promoting air into the fuel bed from the ash pit. The openings 22 are covered by an annular fuel distributing ring 24 which, in the first form of the invention, is particularly constructed to admit a certain amount of air from the openings 22 into the fuel bed and to distribute fuel around the fuel pocket when the stoker is in operation.

Referring to Figs. 4, 5 and 6, the ring 24 is formed on its lower face with a circular groove 25 entirely encircling the ring. Inclined transverse slots extend from the central groove 25 to the outer edge of the ring to provide air ducts leading from the passages 22 to the space within the fire pot. In the first form of the invention the upper surface of the ring is formed with a succession of thumb slots 26 on the upper edge thereof constructed to be engaged by a suitable plunger for moving the ring. The inner reduced edge 28 of the ring extends beneath the flanged edges of securing lugs 30, bolted to the base plate 8. The lugs 30 form anti-friction bearings for preventing its upward displacement during operation of the stoker.

During movement of the ring 24, fuel is distributed about the annular fire pot by means of projecting fingers 32 mounted on the ring 24, and extending upwardly and rearwardly with

respect to the movements of the ring, whereby the fuel is periodically lifted and agitated and distributed around the fuel pocket as the ring is moved. One or more distributing fingers 32 may be employed.

Fuel may conveniently be supplied to the fire pot shown in the first form of the invention by removing the clinker door and placing in its location a plate 34 having a central sleeved portion 35, forming an opening for receiving the fuel feeding pipe 36. The fuel supply pipe 36, secured within the sleeve 35, is preferably inclined slightly as shown and directed over the thumb slots 26 in the ring 24. Fuel is supplied to the pipe 36 through the opening 37 opening into the lower portion of the fuel hopper 38. A plunger 40 slides within the pipe 36, from a position near its open end to a point beneath the opening 37, the extent to which the plunger 40 exposes the opening 37 determining the quantity of fuel added at each stroke. The plunger 40 may be connected by an adjustable link 42 to an eccentric 44 mounted on the vertical drive shaft 45 connected by suitable reduction gearing to the motor 46. At the forward end of the plunger 40, there is mounted a push bar 48 rigidly secured to the plunger 40 and positioned to engage within the thumb slots 26 in the ring 24 as the plunger moves forward. During rearward movements of the plunger 40, the bar 48 is retracted into position to become engaged with other thumb slots during the next forward movements of the plunger. Due to the slight inclination of the tube 36 and plunger 40, as shown in Fig. 1, the bar 48 may be retracted entirely out of contact with the ring 24 and be brought into engagement with one of the thumb slots only during a portion of its next forward movement, thereby moving the ring to the extent of only one or two slots. In this way, the ring 24 is moved to a lesser extent than the total movement of the plunger 40. If desired, a suitable guide for the bar 48 may be provided adjacent the upper edge of ring 24 to assure contact of the bar in the slots 26 and to raise the plunger to prevent it from unintentionally contacting slots 26 when in its fully withdrawn position, thus making certain that the plunger will move the ring one or more slots, as desired.

A forced draft of air is supplied by means of a blower 50 which may be mounted directly on the shaft of motor 46. The blower directs air through the conduit 52 from which the air passes through a duct 53 leading directly to the base of the upstanding wall 9 of the fire pot. Air is thus discharged outwardly through the openings in wall 9 into the body of fuel being consumed. A certain proportion of the air may be admitted directly to the ash pit, if desired, through the opening 54 controlled by the slide valve 55. The division of the air between the ash pit and passage leading directly to the air openings 9a is not essential as the furnace will operate satisfactorily with air supplied only to the openings 9a or with duct 53 omitted and air supplied only to the ash pit space.

It will be noted that in general the draft applied to the fuel in the furnace is outwardly toward the side wall of the boiler to be heated. This is a desirable feature of the invention. Under some conditions additional combustion promoting air is desirable above the bed of fire. For this purpose one or more jet pipes 56 may be employed with air nozzles directed toward the side wall of the furnace. The air supplied

from the pipes 56 serves not only to direct the flames against the side walls but also create a vortex behind the pipes for causing any small particles of ash escaping with the flames to fall into the discharge passage at the center of the furnace.

In the form of the invention shown in Figs. 7 to 11, the same general type of furnace and stoker is disclosed, except that the fuel is supplied beneath one side of the fire pot and forced up into the same from beneath. This permits introduction of the fuel through the ash pit door space. To this end, the plate 57 forming the base of the fire pot is formed with an opening 58 adjacent the outer edge of the plate. A conduit 59 is placed beneath the opening 58 for directing fuel upwardly through the opening, the conduit being formed with a sleeve 60 for receiving the fuel pipe 61, extending to a point without the furnace. The fuel pipe 61 is formed with an opening 61a for receiving fuel from the hopper.

Fuel received within the pipe 61 is advanced in any preferred manner. The devices shown for this purpose include a small steel bar 62 extending through the length of the tube and connected to an operating lever 63, pivoted at 64, and connected by link 65 to an eccentric 66 driven from a suitable motor, as in Fig. 1. A series of advancing lugs 67, carried by the bar 62, are formed with inclined upper surfaces 68 and advancing edges 69, for advancing fuel through the tube on forward movement of the bar. The lugs 67 may be suitably curved on their lower supporting edges, as shown at 70, to conform to the interior curvature of the tube 61. The lugs 67 may be secured individually on the shaft 62 although it is sufficient to employ keys 72 at the forward and rearward ends of the series of lugs to secure the lugs on the bar.

In this second form of the invention, a different type of advancing ring 74 is employed. This ring may be in the form of a T iron, the base of which extends downwardly through a circular opening 76 formed in the base plate 57. The plate in this case is reinforced by cross brackets 78 suitably placed around the plate 57 and spanning the circular opening 76. The ring 74 is provided with projecting fingers 80 so that when the ring is rotated fuel is agitated and advanced around the fire pot. In the form of the invention shown the ring 74 is advanced by means of a construction embodying an advancing lug 82 formed with jaws 84 which clamp the base 75 of the circular T bar when the lug 82 is advanced. The lug 82 is pivotally connected to a yoke 86 carried by an operating link 88, in turn connected to the rearward end of lever 63 beyond its pivot 64. The lug 82 is formed with a projecting end 83 which engages the base of the yoke 86 during rearward movement of the link 88, so that the rearward movement of the link 88 does not move the ring 74. During forward movement of the link 88 and lug 82, the jaws 84 bind upon the base 75 of the ring 74 and advance it to a small extent during each rearward movement of the fuel-feeding bar 62.

It will be understood that the constructions disclosed herein are by way of illustration only and that modifications thereof may be made so long as they fall within the scope of the appended claims.

Having now described my invention, I claim:

1. In a furnace, an annular fire pot therein

and an ash discharge opening, an underfeed stoker for supplying fuel to the lower portion of said fire pot, movable means within said fire pot for evenly distributing fuel around the same and for agitating successive portions of said fuel periodically during normal operation of said stoker.

2. In combination with a furnace having a fire pot, underfeed stoker mechanism for feeding fuel into one side of said fire pot, a movable distributor for moving and distributing said fuel circumferentially around said fire pot, means for supplying a forced air draft into said fuel and means for discharging ash from said fire pot.

3. In combination with a furnace having a combustion chamber, an annular fire pot therein, a fuel feeding device for introducing fuel into said fire pot beneath the upper surface of the fuel therein, a member movable circumferentially around said annular fire pot for distributing fuel therein, means for advancing said movable member by a step by step movement and means for supplying combustion promoting air to the fuel in said fire pot.

4. In combination with a furnace having an annular fire pot and side walls, a fuel feeding device for introducing fuel into said fire pot, means for supplying combustion promoting air to the fuel in said fire pot and means for directing an additional draft of combustion promoting air over the fuel in said fire pot outwardly toward the side walls of said furnace.

5. In combination with a furnace, a fuel support comprising an annular fire pot within said furnace, means for introducing solid fuel into one portion of said fire pot beneath the fuel therein and rotatably movable means for distributing said fuel substantially uniformly around said fire pot from the place of introduction.

6. In a furnace, a fire pot having an annular base and formed with an upwardly projecting central ash discharge outlet duct, means for introducing fuel into the lower portion of said fire pot, and a mechanical fuel distributing member supported for movement over the base of said fire pot for distributing fuel therein.

7. In a fuel supply device for furnaces, a fuel support, a hollow upstanding member of frustoconical form positioned centrally of said support and including a central ash discharge outlet, means for introducing fuel onto said support below the level obtained by the fuel during operation of the device, and mechanical means movable around said upstanding member for evenly distributing said fuel about said support during said operation.

8. In combination with a furnace having a combustion chamber, a fire pot therein having an annular base, a feeding device for introducing fuel into the lower portion of said fire pot, an annular distributing ring supported on said base, fuel distributing members carried by said ring, means for moving said ring circumferentially around said fire pot for distributing and agitating the fuel therein and means for supplying combustion promoting air to the fuel in said fire pot.

9. In a furnace, an annular fire pot having a

central ash discharge opening, means for introducing fuel into the lower portion of said fire pot, an annular distributing member rotatably mounted on the base of and located within said fire pot and including fuel distributing elements, means for moving said distributing member, and means for removing furnace ash discharged through said opening.

10. In combination with a furnace having a combustion chamber, a base plate and an upstanding hollow central wall forming with the outer wall of said furnace an annular fire pot at the base of said combustion chamber, a fuel feeding device for introducing fuel into said fire pot, means for supplying combustion promoting air under forced draft directly to the inner margin of said fire pot along said central upstanding wall and at the upper edge thereof, and means for supplying additional combustion promoting air at points remote from the inner margin of said fire pot including means for directing a draft of combustion promoting air over the fuel in the fire pot and outwardly toward the outer wall of the furnace.

11. In a furnace, a fire pot having an annular base and a central overflow ash discharge outlet, means for supplying fuel into the lower portion of the fire pot, an annular ring supported on said base, fuel distributing means carried by said annular ring, and means operating in conjunction with said fuel supplying means for intermittently moving said annular ring.

12. In a furnace, a fire pot having an annular base and a central overflow ash discharge outlet, means for supplying fuel into the lower portion of the fire pot, an annular ring supported on said base, fuel distributing means carried by said annular ring, and reciprocable means operated from said fuel supplying means for imparting a step by step rotating movement to said annular ring.

13. In a furnace, a fire pot having an annular base and a central overflow ash discharge outlet, means for supplying fuel into the lower portion of the fire pot, an annular fuel distributing ring supported on said base, reciprocable means operated from said fuel supplying means and supported and arranged to contact said ring to impart movement thereto upon forward movements of the reciprocable means and to be out of operative engagement with the annular ring on rearward movements of the reciprocable means.

14. In a furnace, a fire pot having an annular base and a central overflow ash discharge outlet, means for supplying fuel into the lower portion of the fire pot from below the base thereof, a fuel distributing annular ring supported on said base and including a portion extending through said base, and reciprocable means operating in conjunction with said fuel supplying means and arranged to be in operative relationship to said extending portion of said ring upon forward movements of the reciprocating means to rotatably move said ring, and to be out of operative relationship to said extending portion upon rearward movements of said reciprocating means.
